UNITED STATES PATENT OFFICE

JAMES W. BRYCE, OF BLOOMFIELD, NEW JERSEY, ASSIGNOR TO INTERNATIONAL TIME RECORDING COMPANY OF NEW YORK, OF ENDICOTT, NEW YORK, A CORPORATION OF NEW YORK

SECONDARY CLOCK

Application filed June 25, 1925. Serial No. 39,459.

This invention relates to secondary clocks and more particularly to electrically driven secondary clocks which are driven and maintained in synchronism by electrical energy controlled by both a master clock and the secondary clock.

It has for its object the development of improved features which enables the secondary clock to receive electrical impulses over either one of two lines and make use of them according to its chronological condition of agreement or disagreement with a master clock which sends out the electrical impulses, and to cause the secondary clock to be stepped ahead if it be slow, or to stop altogether if it be fast for a period of time equal to the amount that it is fast, and then resume normal operation.

Other objects have in view the improvement of the construction of secondary clocks of the class described whereby a compact self-contained driving unit for the hands of the secondary clock is produced which consists of a minimum number of parts assembled and designed to facilitate assembly and to lend itself to ease and precision in adjustment.

With these and incidental objects in view the invention consists of certain novel features of construction and combination of parts, the essential elements of which are set forth in the appended claims and a preferred form of embodiment of which is described hereinafter with reference to the drawings which accompany and form part of the specification.

In the drawings:

Fig. 1 is a rear view of the secondary clock driving mechanism assembly.

Fig. 2 is a plan view of the secondary clock driving mechanism assembly.

Fig. 3 is a sectional view on line 3—3 of Fig. 1.

Fig. 4 is a detail of the ratchet and ratchet-wheel drive for the minute hand arbor as seen from above.

Fig. 5 is an elevational detail of the ratchet and ratchet-wheel drive viewed from the rear.

Fig. 6 is an end view of the electrical contacts viewed from the left of Fig. 1.

Fig. 7 is a perspective view of the frame plate which supports the driving mechanism.

The secondary clock mechanism is for use in the secondary clocks of the synchronizing clock system known to the trade as the "I. B. M." or "Bryce" system. In this system, a master clock such as that described in my Patent No. 1,390,018 may be used to drive the secondary clocks. For use with the secondary clock about to be described, the master clock controls the sending out of all impulses once every minute for the entire hour over one line, and also over another line for a definite period of time during the hour. Just after the 59th minute a series of fast or acceleration impulses are sent out over the former line to rapidly advance the secondary clocks that are slow. The period of time preceding the sixtieth minute impulse is called the synchronizing period and the master clock is designed to have this period start on the forty-fifth minute impulse. The controlling devices in the secondary clock about to be described are designed and related to each other so as to cause the secondary clock to be changed over from one line to the other at fourteen minutes past the hour as indicated by the hands of the secondary clock. Any other divisions of time for distributing the electrical energy over different lines could be used, but the above described division has been chosen by way of illustration.

The synchronization of the secondary clocks occurs during the synchronizing period and it is dependent upon the utilization of electrical energy sent out in the form of impulses by the master clock. The utilization of these impulses is controlled by devices herein described which are a part of the secondary clock driving mechanism and which are dependent in their controlling function on the chronologic condition of the particular secondary clock with which they are associated. These devices selectively determine whether the secondary clock shall be connected to receive normal minute impulses, a series of fast impulses, or whether it be connected so as not to receive any impulses for a time.

Having more particular reference to the

drawings, 10 is the main supporting plate for the entire device, and it may be secured to a frame piece, not shown, by means of bolts engaging in holes 11. Extending rearwardly from plate 10 is a shelf 12 which forms a lower support for the rear plate 13 which is held in spaced relation to the front supporting plate 10 by means of rods 14 disposed therebetween. The minute hand arbor 15 is journaled at its forward end in a raised portion 16 of the front supporting plate and at its rearward end in plate 13. Mounted on minute hand arbor 15, just in front of raised portion 16, is a small gear 17 which drives gear 18 loosely mounted with pinion 19 on a stud extending from front supporting plate 10. Pinion 19 drives gear 20 fast to sleeve 21, loosely journaled on minute hand arbor 15, to which is attached the hour hand. Gear 20 and sleeve 21 are kept from longitudinal displacement on the minute hand arbor by means of finger 22 detachably secured to front plate 10. The removal of the finger allows for easy removal of gear 20 from a position in front of plate 10 through the opening in the plate (Fig. 7).

Just forward of the rear plate there is mounted on minute hand arbor 15 ratchet-wheel 23 subject to be actuated by ratchet 24 pivotally mounted upon the upper end of an armature 25 which is itself pivotally mounted near its lower end by means of hinge pin 26 that rests in a groove in the bottom surface of clip 27. This clip is fastened to shelf 12 by any suitable means such as screws 28. Retaining plate 29 is provided to maintain the hinge pin within its groove.

The lower end of armature 25 is urged in a counterclockwise direction (Fig. 1) by a spring 30. When electromagnet 31, which is supported from the upstanding end of clip 27, is energized, it attracts armature 25 against the tension of spring 30 so as to cause ratchet 24 to move clockwise and engage the tooth next ahead of its idle position. Upon deenergization of the electromagnet, spring 30 operates to advance the ratchet-wheel one tooth distance, which movement is limited by the engagement of an ear 32 with the under side of an arm 33 extending from front plate 10. This engagement causes the ratchet to be wedged against the ratchet-wheel and prevents it from being displaced. Retrograde movement of the ratchet-wheel and associated parts is prevented by a spring pressed pawl 34 pivotally mounted on rear plate 13.

Adjustably mounted on the rear plate by means of screws 35, 36 is a supporting plate 37 for the lever arms 38 and 39 which are pivotally mounted on an eccentric bushing supported on a bolt 40. Lever 38 has a stud 41 which rides on the periphery of cam 42 and lever 39 has a stud 43 which rides on the periphery of cam 44. Both cams 42 and 44 are secured to the minute hand arbor and are

staked together by pin 45 when they are accurately adjusted in relation to one another for reasons that will appear hereinafter. Lever arms 38 and 39 are held against the cams by springs 46 and 47 respectively.

On lever arm 38 there is mounted an insulation support for contacts 48 and 49. Lever arm 39 carries a blade 50 which is electrically insulated from the lever arm. On the lower side of blade 50 there is a resilient blade adapted to coact with contact 48 and another resilient blade on the upper side of the blade 50 is adapted to coact with contact 49 when contact 48 is open. One or the other of these resilient blades maintains contact with its respective contact while cams 42 and 44 are stepped around. Cam 42 is designed to allow lever arm 38 to drop on the fifty-ninth minute and close the line connected with contact 49. At fourteen minutes past the hour, lever arm 39 and blade 50 will drop off of the high portion of cam 44 and the line connected with contact 48 will be closed. The adjustability of levers 38 and 39 by the positioning of plate 37 and adjustment of the eccentric bushing on bolt 40 makes it possible to very accurately locate the exact timing to obtain the making and breaking of contacts 48 and 49 outlined above.

Current is supplied to actuate the above described clock movement through two lines, A and B, which are respectively connected to contacts 48 and 49 through binding posts 51 and 52 secured to block 53. This block also carries binding post 54 for the single return wire of the system. From this latter binding post a lead connects the electromagnet in series with blade 50 and the position of blade 50 and contacts 48 and 49 determines which of lines A or B is connected to supply the electrical energy to operate the electromagnet. A non-conducting terminal supporting bar 55 is provided for attaching the leads of the electromagnet in a convenient location.

My invention is capable of a wide variation and relationship of parts without departure from the nature and principle thereof, and I do not restrict myself unessentially in the foregoing or other particulars, but contemplate such alterations and modifications within the scope of the appended claims as may be found advisable.

What I claim is—

1. A secondary clock having driving mechanism, an impulse magnet, synchronizing control means, a minute shaft, and comprising in combination, a supporting structure which comprises a front plate and a rear plate, means for supporting the impulse magnet between the plates, means also disposed between the plates for operating the minute shaft from said impulse magnet, said minute shaft extending rearwardly beyond the rear plate, two contact cams carried on

5 said minute shaft in accessible position beyond the rear plate, said synchronizing control means comprising one arm pivotally mounted in accessible position rearwardly of the rear plate and carrying two contact points and coacting with one of the cams and a second arm also disposed rearwardly of the rear plate and coacting with the other of said cams and carrying a switch blade, and

10 another plate secured to the rear plate for pivotally supporting said arms.

15 2. A secondary clock structure which includes a driving mechanism with an impulse magnet for actuating the same, a minute shaft, and a synchronizing control means, and including in combination, a supporting structure including a front plate and a rear plate with provisions for supporting the impulse magnet and the driving mechanism between the said plates, said rear plate having provisions associated therewith for supporting the synchronizing control means in accessible position rearwardly of said rear plate whereby ready access may be had thereto for

20 25 inspection, adjustment and repair.

3. The invention set forth in claim 2 in which a binding post block is provided also mounted upon the rear plate and in accessible position from the rear of said plate for the

20 25 making of electrical connections.

4. The invention set forth in claim 2 in which the synchronizing control means comprises two contact cams mounted upon an extension of the minute shaft which projects rearwardly beyond the rear of the rear plate so as to be in visible accessible position thereon and contact arms cooperating therewith and provided with switching means, and in which means comprising a plate, which is fastened to the rear plate, is provided for supporting the arms of the synchronizing control means in accessible position rearwardly of said rear plate.

5. A secondary clock having the usual indicating hands, actuating impulse magnet and synchronizing control means, and comprising in combination, a main supporting plate-like frame having an extension therefrom, and a supplementary plate spaced from and secured to the first mentioned plate, means comprising an L-shaped plate attached to an extension from the first mentioned plate for supporting the impulse magnet between the aforesaid plates, and means for supporting the synchronizing control means from the supplementary plate upon the opposite side thereof from the said impulse magnet to provide for accessibility of said control means for adjustment, inspection and repair.

6. The invention set forth in claim 5 in which the synchronizing control means comprises a pair of contact controlling arms, and in which means is provided for adjusting the time of action of said arms, which means

65 comprises an eccentric bushing which is

mounted back of the supplementary plate so as to be in accessible position for adjustment.

In testimony whereof I hereto affix my signature.
